FOUNDATION BORING MACHINE

Edward T. Shinn, Harrison, N. J.

Application December 28, 1933, Serial No. 704,335

6 Claims. (Cl. 255—19)

This invention relates to an improved foundation boring machine, the object being to provide a construction wherein various sized holes may be bored in the earth to varying depths.

5 Another object of the present invention is to provide a machine for boring comparatively large holes in the earth to varying depths, the same being of a size to receive concrete or other material to form a foundation for a building or 10 other superstructure.

A further object of the invention is to provide a boring machine for boring holes in the earth wherein the power means and the various controlling members of the boring apparatus are 15 caused to function through a remote control so that the operator may remain at a distance from the boring machine.

An additional object of the invention is to provide a boring apparatus having a remote control, 20 the structure being such that the power means for actuating the device is carried immediately adjacent the boring head.

A still further object of the present invention is to provide a boring machine for boring holes of 25 different diameter, the structure including power means carried near the boring head with part of the means acting to open and close the head, so that at one time it acts as a boring head and at another time as a bucket for elevating and dis- 30 charging the matter removed.

In the accompanying drawings—

Figure 1 is a side view of a foundation boring machine disclosing an embodiment of the invention, part of the machine being shown in section 35 for better illustrating certain details;

Figure 2 is a longitudinal vertical sectional view through the head and control mechanism shown in Figure 1;

Figure 3 is a vertical sectional view through 40 Figure 2 approximately on the line 3—3;

Figure 4 is a horizontal sectional view through Figure 2 on the line 4—4;

Figure 5 is a horizontal sectional view through Figure 2 on the line 5—5;

45 Figure 6 is a detailed perspective view showing the arrangement of pulleys and cables embodying certain features of the invention;

Figure 7 is a diagram showing the wiring for the remote control mechanism used in controlling 50 the power means shown in Figures 2 to 4, inclusive;

Figure 8 is an enlarged fragmentary sectional view through Figure 1 approximately on the line 55 8—8.

55 Referring to the accompanying drawings by

numerals, 1 indicates a truck of any desired kind provided with a crane 2 for supporting the boring apparatus 3, and for accommodating certain elevating cables hereinafter fully described. The boring apparatus 3 includes pulleys 4 and 5, as shown in Figure 6, said pulleys accommodating the elevating cable 6, which also passes over pulleys 7 and 8, pulley 8 being supported by the shaft 9. Auxiliary pulleys 10 and 11 are also carried by shaft 9, said auxiliary pulleys accommodating suitable cables 12 and 13 used in raising the crane 2. By the arrangement of pulleys and cables 6 as shown in Figures 1 and 6, the boring structure 3 may be raised at any time or lowered by paying out cable 6. The boring apparatus 3 is provided with a casing 14 in which an electric motor 15 is mounted.

A square shaft or rod 16 is rigidly secured in any desired manner, for instance, by bolts, to the upper end of casing 14. This rod or shaft is provided with an enlarged square head 17 at the upper end slidingly fitting into the square shaft 18 which has a bead 19 slidingly fitting into the shaft 20, which latter shaft is provided with a bead 21. The respective square shafts are readily seen in their proper relation by an examination of Figure 8. Shaft 20 is guided by a guiding disc 22 which is pivotally mounted through the use of certain journals at 23 and 24 (Fig. 8), said journals rotatably fitting in a ring 25 which has the 30 journal members 26 and 27 rotatably fitted into the bearings 28 and 29 carried by the upper end of the crane 2. This arrangement provides an effective guide for shaft 20 and associated parts but allows the same to freely swing in any direction, though the shafts cannot rotate in a horizontal plane, thus providing an abutment against which the torque of motor 15 acts when this motor is rotating the boring head 30. The use of the various telescoping shafts as illustrated in 40 Figures 1 and 8 is in order that the boring head 30 may be caused to operate at different distances according to the length of the various shafts above mentioned.

The device is adapted to drill a hole in the earth 45 for a few feet or for a great number of feet, say seventy-five or possibly one hundred feet, depending on the length of the guiding shafts 16, 18 and 20. It is to be understood that in operation when boring a hole the boring head 30 is lowered 50 and allowed to rest on the ground. At the same time this head is rotated by the main driving motor 15 until the head becomes filled or partly filled with earth. The motor may then be stopped and the cable 6 pulled for raising the boring struc- 55

ture 3. After the boring structure, including the head 30, is swung to one side by the crane 2, certain mechanism hereinafter fully described is operated for opening the bottom of the head 30, whereby the earth therein will be allowed to drop out under the action of gravity. The boring structure 3 is then swung back over the hole and lowered until it strikes the bottom of the hole. Motor 15 is then started and the head rotated until it again becomes filled and the operation just described is repeated. This action is repeated as often as may be necessary to secure the desired depth of hole. The drilling of a comparatively large hole, for instance, four to six feet, is especially desirable to provide foundation pillars or columns, though the holes could be used for any purpose.

The casing 14 which encloses the main driving motor 15 guides at its lower end a shaft 31, which shaft is rigidly secured to the armature or rotating element of the motor 15 so that the shaft 31 will rotate whenever the motor 15 rotates. The connection of shaft 31 to armature or the rotating part of motor 15 is through any desired form of reducing gear (not shown) whereby shaft 31 will rotate rather slowly while motor 15 operates at a high rate of speed. In this way power from the motor is multiplied and the head 30 and associated parts are rotated at a desired speed. Shaft 31 is keyed or otherwise rigidly secured to plate 32, which plate has a sleeve 33 extending upwardly therefrom and surrounding most of shaft 31. In addition a nut 31' is used as shown in Fig. 2 whereby the weight of the parts below the motor may be readily supported. A number of slip rings 34 are carried by the sleeve 33 but insulated therefrom by a suitable insulation 35. A supporting bar 36 is bolted or otherwise rigidly secured to casing 14 which supports a number of spring contacts 37, 38, 39, 40, 41 and 42. The contacts 37 to 42, inclusive, continually engage the various rings 34 so that there will always be a contact between the two members notwithstanding the movement of the insulating sleeve 35 with its plate 32. These contacts and associated parts are shown in the diagram in Figure 7 and the function of these parts will be described fully hereinafter. Plate 32 is rigidly secured to a number of posts 43 by bolts or other means, said posts being rigidly secured to or integral with the base 44 which, through the respective bolts 45, is rigidly secured to the bar 46. Bar 46 is in the nature of a cross as illustrated particularly in Figure 2 and at the outer part thereof carries the drum which is welded or otherwise rigidly secured to the respective arms of bar 46. This drum forms part of the boring head 30, as is true of the bar 46.

Referring again to the posts 43 it will be seen that some have secured thereto a cross bar 48 which is adapted to support the idler gear wheel 49 which continually meshes with the pinion 50 and the large gear 51. Pinion 50 is connected to the rotating part of the electric motor 52, which motor is supported by one of the posts 43 by a suitable bracket 53. It will be noted that the motor 52 is positioned vertically as this is the most convenient manner to position the same so as to transmit power to the large gear 50 which is rigidly secured to the threaded shaft 54 extending downwardly through base 44 and bar 46.

Shaft 54 is screwed into an internally threaded sleeve 55, this sleeve merging into a solid portion 56 at the lower end, said solid portion being apertured for accommodating the bar 57 which

is connected to the solid portion 56 by the pin 58. A guiding tube 59 is provided with an enlarged upper end 60 as shown in Figure 3 whereby the bolts 64 may clamp the tube to the bar 56 and permit the tube to readily guide and hold in place the threaded sleeve or shaft 55. A sliding sleeve 62 is loosely fitted over the tube 59 and slides thereon for purposes hereinafter fully described. It will be noted that the tube 59 is provided with slots 63 and 64 for accommodating the bar 57 so that when the shaft or sleeve 55 moves upwardly and downwardly bar 57 may readily slide in these slots, sleeve 62 sliding freely over the tube 59. The tube 59 extends downwardly to a point substantially in line with the bottom of the boring head 30 when closed, said tube accommodating a hollow pointed head 65 having a number of apertures 66, said head having a tubular portion 67 fitting into the lower end of tube 59 whereby air may freely pass downwardly and mix with the earth being excavated. It will be understood that as the sleeve 62 is loose, air may freely pass into the interior of tube 59 and thence out through the openings in the head 65, said head acting as a centering extension for centering the boring head 30 when in operation. The bars or cables 68 and 69 are pivotally mounted on the outer ends of bar 57 and pivotally connected at 70 and 71 to the leaves 72 and 73 of the hinges 74 and 75, which hinges connect the blades 76 and 77 to the drum 47. Any desired number of pins 78 may be connected to drum 47 and extend into suitable notches in the respective blades 56 and 57 so as to take the strain off the hinges during the operation of the boring head 30.

From Figure 5 it will be seen that the respective blades 76 and 77 are provided with cutters 79 and 80 which are preferably removable, said cutters being held in place by any desired means as, for instance, bolts or rivets. When the blades 76 and 77 are closed the device is in position for operation, there being sufficient opening in front of each of the cutters to admit the earth as the boring head is rotated. After the boring head has been filled or partly filled with earth and it is desired to dump the same, the entire structure is pulled out of the hole, swung to one side, and then motor 52 is set into operation, whereupon the threaded shaft 54 will be rotated in such a direction as to force the sleeve 55 downwardly, and as it moves downwardly it will force bar 57 and associated parts downwardly, whereupon the blades 76 and 77 will be lowered to the dotted position shown in Figure 2, thus permitting a dumping operation. After dumping the contents, motor 52 is reversed and the parts moved upwardly to the position shown in Figure 2, whereupon the device is ready to be lowered into the hole for further operation.

The motor 52 is set into operation by closing a switch at a distant point, thus permitting the motor to be actuated through the use of a remote control. However, when the motor has been started by the remote control it is automatically stopped by certain means as shown in Figures 2 and 7. As illustrated in Figure 2 a bracket 81 is secured to the sliding sleeve 62, said bracket having an aperture therein so that the rod 82 may slide freely therethrough. This rod is provided with abutments 83, 84 and 85. Preferably these abutments are nuts threaded into position so that they may be readily adjusted as desired. Coacting with the rod 82 are switch arms 86 and 87. These arms coact with the contacts 88 and 89.

89. These switch arms are spring pressed so that whenever released they will engage their respective contacts. When in the position shown in Figure 2 switch arm 87 is shown closed, while switch arm 86 is shown open. As the sliding sleeve 62 moves downwardly bar 57 will also move downwardly and will carry with it the bracket 81. Shortly before the bar 57 reaches the lowermost end of its movement bracket 81 will strike 10 the abutment 83 and will move this abutment and rod 82 downwardly as the sleeve continues its downward movement. The parts are so proportioned that rod 82 is pulled downwardly sufficiently to release arm 86 so that it will engage 15 contacts 88, and a little later engage and open the switch arm 87. Switch arm 87 remains open until through action of the remote control the motor 52 receives current in a reverse direction to raise the various parts, which when raised 20 will automatically permit the arm 87 to close and will almost simultaneously open arm 86.

It will be understood that suitable wiring as hereinafter described and as shown in Figure 7 is provided and extends from the various switch 25 arms just mentioned and from motor 52 to a suitable distant point as, for instance, a switchboard on the truck 1 as shown in Figure 1. It will be further noted that the motor 52 acts to open and 30 close the boring head 30, while motor 15 acts to rotate the boring head and associated parts. The boring head 30 and associated parts are raised and lowered by any hoisting drum associated 35 with the cable 6. The various parts will function as just described and bore a hole of a given diameter, for instance, 4 feet in diameter.

However, under some circumstances it may be desired to bore a hole of greater diameter as, for instance, a five foot hole. When this is the case some auxiliary mechanism is brought into 40 play, the same being shown particularly at the upper part of Figure 2 and also in Figure 4. In these two figures it will be seen that there are provided cutters or boring members 90 and 91, said members having turned up ends 92 and 93 45 and cutting edges on these ends and at part of the body of the boring tools. These boring tools are slidably mounted on the base 44 and have brackets 94 and 95 connected therewith rigidly by bolts or other suitable means. These brackets 50 at the upper ends are preferably forked so as to straddle the reduced portions 96 and 97 of the respective traveling nuts 98 and 99, which nuts are mounted on a right-and-left hand threaded rod 100. This rod is mounted in suitable journal 55 members in the posts 43. A small gear wheel 101 is rigidly secured to shaft 100 near one end and continually meshes with the idler pinion 102, which in turn continually meshes with the gear wheel 103 rigidly secured to the moving part of 60 the electric motor 104, which motor is supported by a suitable bracket 105, said bracket being bolted or otherwise rigidly secured to one of the posts 43. It will, therefore, be seen that when motor 104 operates in one direction the traveling nuts 65 98 and 99 will be moved toward each other and the ends 92 and 93 of the cutters will also be moved toward each other. It will also be noted that when motor 104 is reversed the various parts will move in a reverse direction. By causing the 70 motor 104 to function properly the cutters may be moved outwardly or inwardly to any desired extent within the limits of the machine.

It will be understood that when in operation the boring head 30 will first bore a hole of the 75 diameter of the drum 47 until the cutters 90 and

91 engage the earth, whereupon these cutters will enlarge the hole and allow the loosened earth to fall into the drum 57, said drum being open at the upper end. This action is carried out for the full depth of the hole whether it is ten feet or 5 seventy-five feet. The motor 104 is controlled by a remote control mechanism shown particularly in Figure 7, whereby it may be moved as desired on the control board which may be placed in the cabin of the truck 1 so that it may be conveniently operated. 10

When using the cutters 90 and 91 they may, if desired, be drawn inwardly whenever the boring head 30 is removed so as not to interfere with the easy removal of the loaded boring head. After 15 dumping the cutters 90 and 91 are moved outwardly to their former position so that they will be in proper position for operation when the boring head is lowered into the bottom of the hole. Connected with one of the traveling nuts 98 and 20 99 is a mechanism similar to rod 82 and associated parts, the same having been omitted from Figure 2 so that the figure may be more easily read. However, the mechanism and function thereof is exactly that set forth in regard to the rod 82 25 and associated parts. This mechanism has been shown in diagram in Figure 7 as well as the rod 82 and associated parts.

Referring more particularly to Figure 7 the various circuits will be traced and from these 30 circuits it will be readily seen that the parts may function as hereinbefore described.

As illustrated in Figure 7, the wires 106 and 107 are the feed or bus lines, and to these wires are connected suitable feed wires 108, 109 and 110. 35 Wires 109 and 110 are positive while wire 108 is negative. A suitable switch 111 is provided so that current may be readily turned on and off. When switch 111 is closed current will pass through the positive wire 109 to the spring contact 37 and to wire 112. Current from the bus-wires 106 and 107 is adapted to pass through wires 113 and 114 to the motor 15 whenever the control rheostat 113' is turned on, whereby the motor 15 may be caused to function at any time 40 and may be stopped at any time without interfering with the operation of any of the other parts. Current will pass from wire 112 to the armature of motor 52, and also through wire 112' 45 to the armature of motor 104. From these motors current will pass to the return wire 116, to the negative wire 115, then back through the spring contact 38 to wire 108, and thence to the bus wire 106. It will thus be seen that when switch 111 is turned on current will be supplied to 50 the armatures of motors 52 and 104, but these latter two motors will not function until current is supplied to their fields 117 and 118. If the parts are in operative position and the boring head is being lowered, motors 104 and 52 will remain idle as the head is lowered, though motor 15 will continue to function and will be allowed to operate until the boring head is filled or partly 55 filled with earth and again raised to the surface. However, after the loaded boring head has been raised from the hole and swung to one side, the blades 76 and 77 must be opened. Preferably the switch 119 is a push button arranged so that it will open immediately upon being released. 60

The same is true of the switches 120, 121 and 122. All of these switches have one side connected to the wire 110 while the other side is connected to the respective wires 123, 124, 125 and 126. When the switch 119 is closed current will 75

flow through wire 123 to the spring contact 39 and thence to wire 121. Current flowing through this wire will pass into wire 128, through the windings of magnet 129, through wire 130, back 5 to the negative wire 115, thus completing the circuit of the magnet 129. This will almost instantly cause the magnet to move the bar 131 so as to close the respective contacts 132 and 133. It will be understood that these contacts are 10 closed almost simultaneously with the energization of the magnet 129 and, consequently, current will flow through contact 133, wire 134, contact 89, arm 86, wires 135 and 136 to the field windings 117 of motor 52, and through these windings current will flow through wire 137 to contact 132, thence through wire 138 back to the negative wire 115. It will thus be seen that when the switch 119 is closed current will be supplied to the magnet 129, and current will also be supplied to the field 117 of motor 52 so that this motor will begin to function and will move the bar 57 (Fig. 2) downwardly, together with all the parts associated therewith. As these parts move downwardly the blades 56 and 57 will be opened 15 and bracket 81 will eventually strike abutment 83 and move rod 82 downwardly until arm 86 is released and arm 87 disengaged from its contact 89. As soon as this disengagement takes place the windings 117 will be deprived of current and motor 52 will stop automatically even though switch 119 is maintained closed.

The operator can readily see when the boring head 30 has been dumped and can then remove his hand from the switch 119. To close the 35 blades 76 and 77 the operator leaves switch 119 open and closes switch 120. As soon as switch 119 is opened the entire line, including the magnet 126, will be deprived of current, but as soon as switch 120 is closed current will flow through wire 124 to spring contact 40 so as to energize the wire 139. Current flowing in this direction will pass through the windings of magnet 140 so as to energize the same, and will then flow back to wire 141 to the negative wire 115. The 40 energization of magnet 140 will pull upwardly on the bar 142 so as to close the respective contacts 143 and 144. These are closed almost simultaneously with the energization of magnet 140 so that current will flow through the wire 145 to contacts 45 144 and through these contacts to wire 146, contact 88, arm 86, wire 147, wire 148 to and through field windings 117, and then back through wire 148, contact 143 and wire 141 to the negative wire 115. This will energize the motor 52 so as to cause the same to run in a reverse direction and thereby pull upwardly on bar 57 (Fig. 2). This 50 upward movement is continued until the blades 76 and 77 are closed. Substantially at the time of closing of these blades the bracket 81 will strike the abutment 84 and raise rod 82 so that abutment 85 will raise the arm 86 and disengage the same from contact 88, thus opening the circuit of the field 117 and thereby causing the motor 52 to stop. It will be noted 55 that the motor stops even though switch 120 is maintained closed. As long as switch 120 is closed the magnet 140 will remain energized, but as soon as the operator sees that the boring head has been closed he releases switch 120 and then 60 manipulates the crane so as to allow the boring head to be again lowered into the hole for further boring operation. It will be noted that no one is near the boring head during operation thereof as all the controls are arranged at a distance with the opening and closing of the blades 65 70 75

76 and 77 automatically stopped at the proper places.

The switches 121 and 122 are identical with switches 119 and 120. The various wires are also identical but are used in connection with the motor 104 for moving the cutters 90 and 91 in and out. It is therefore thought that no additional description thereof will be necessary as the construction and operation are identical.

I claim:—

1. A foundation boring machine including a hollow boring head having a bottom divided into two parts and swingable to an open and closed position, means for swinging said bottom, and a guide for guiding said means, said guide extending to a point above the head, said means including a reciprocating tubular member arranged centrally of the head and surrounding said guide, a bar carried by said tubular member, and links for connecting said bar to said two parts.

2. A foundation boring machine including a boring head having a top member, a guiding tube extending from said top member downwardly, an apertured piercing head carried at the bottom of said tube whereby air may be distributed, a drum connected to said top member, a pair of blades connected to the bottom edge of the drum and forming a bottom formation arranged above the apertured head so that air may be discharged into the material being excavated during the excavation operation, a cutter member for each of said blades, and means for swinging said blades whereby when they are in one position the drum will be closed and when in another position the drum will be sufficiently open to allow any material therein to drop therefrom under the action of gravity.

3. A foundation boring machine including a boring head of a certain diameter, a pair of boring blades arranged above said boring head, means for moving said blades radially so that they may extend beyond said boring head to enlarge the hole produced by said head, a power motor for rotating said head and said boring members, and a remote control structure for controlling the actuation of said power motor and the means for moving said boring members.

4. A foundation boring machine including a boring head, means for driving said boring head, an auxiliary boring structure comprising a pair of sliding cutters and means for sliding the cutters inwardly and outwardly radially, and a remote control structure connected to said last mentioned means and to the means for rotating said boring head.

5. A boring foundation machine including a boring head, an electric motor for rotating said head, an auxiliary boring structure connected with said head and rotated therewith, said auxiliary boring structure including a pair of radially slidable cutting blades, a threaded structure for moving said blades inwardly and outwardly, an electric motor for rotating part of the threaded structure for causing the threaded structure to function, and independent means at a remote point for independently controlling the rotation of the first mentioned electric motor and the rotation of the last mentioned electric motor, said last mentioned motor being capable of being reversed by controls at said remote point.

6. A foundation boring machine comprising a lift boom having a guiding member at the top, means acting on said guiding member and on said lift boom for raising and lowering said unit, said

unit including a plurality of telescoping squared shafts each shaft being provided with an enlarged end whereby an up-and-down movement of the parts may be secured while still engaging said guiding member, a frame connected with the innermost of said shafts, an electric driving motor carried by said frame, and a boring head supported and driven by said driving motor, said telescoping

tubular shafts permitting an up-and-down movement of said boring head within the limits of the machine without the outermost tubular shaft moving out of contact with said driving means, whereby the electric motor carried by said frame may always react against said tubular shafts as it drives said head.

5

EDWARD T. SHINN.
